UNITED STATES PATENT OFFICE

ALDO CURIONI, OF LARCHMONT, NEW YORK

MACHINE FOR STITCHING PATTERNS ON FABRIC BASES

Application filed May 17, 1928. Serial No. 278,387.

The present invention relates to machines for use in the textile and weaving industry, particularly those for making plush surfaces such as rugs, tapestries, etc. In the manufacture of hooked rugs and similar articles, where the machinery is automatic, the machines are highly complicated and expensive. Their utility is greatly impaired by the difficulty in keeping them in repair, in addition to the great initial expense.

The present invention has for an object, the provision of a machine which produces the above articles very economically and quickly. By providing a bank of needles upon a frame which is movable relative to a frame carrying a suitable fabric to serve as a base, the needles may be reciprocated with respect to the fabric and, as they pass in and out thereof, the friction of the thread in the fabric holds it in a series of loops as the needles are withdrawn. The fabric may be moved in a manner which will produce a predetermined arrangement of loops of various colors and certain of the needles may be cut in and out during certain of the reciprocations of the needle frame to form irregular figures and designs in the fabric base.

It will be apparent that the needles forming the loops may be spaced in varying degrees of proximity and the resulting loops formed at each reciprocation of the needle frame will be equal to the number of needles carried by the reciprocating frame. The spacing of the loops may be varied by changing the lateral movement of the fabric frame between reciprocations of the needle frame. After a desired figure or design has been worked in the fabric, the loops formed on the side away from the needle frame are cut to form a pile surface.

Further objects will be apparent as the description of the invention proceeds and reference will now be had to the accompanying drawings, wherein:

Figure 1 is a view in section, taken on line 1—1 of Figure 2 and looking in the direction of the arrows.

Figure 2 is a plan view of a simple form of machine embodying the present invention.

Figure 3 is a perspective view of the needle

used in the machine shown in Figures 1 and 2.

Figure 4 is a view in section, showing the fabric with several loops formed therein, and indicating the line upon which the loops are cut after the fabric is removed from the frame.

Figure 5 is a view in section taken on line 5—5 of Figure 2 and looking in the direction of the arrows, this view showing the manner in which the carriage is held by the guide plate.

Referring to the above drawings, *a* designates a suitable base with legs *a'*. Screws *a*² secure a foot plate *b* to the base *a* and an inverted U-shaped standard *b'* serves as a guide for a carriage *b*². The bridge portion of the U-shaped standard *b'* carries a set screw *b*³ for adjusting the vertical position of the carriage *b*², causing the latter to be moved up and down between the guides *b'*.

A dovetailed groove *b*⁴ is formed in the carriage *b*² and receives the dovetailed tongue *c*' of a fabric frame *c*. In the form shown, this fabric frame comprises a cup shaped member with a tapered outer periphery *c*². A cooperating clamping ring *d*, formed with a similar taper on its inner surface, is clamped to the periphery *c*² by means of oppositely spaced bolts *d*', pivoted to the frame *c* at *c*³ and carrying thumb nuts *d*². Within the frame, a brush *e* is provided having bristles *e*' which are tightly squeezed together as the brush is inserted in the frame and a fabric *f* is placed over the ends of the bristles and secured between the clamping ring *d* and the outer extremity *c*² of the frame.

A bracket *b*⁵, carrying a thumb screw *b*⁶ which engages the fabric frame *c*, provides a means for moving the fabric frame transversely with respect to the base plate *a*.

Formed on the opposite end of the base plate is a longitudinally extending guide plate *g* having oppositely disposed and outwardly extending flanges *g*'. A carriage *h*, having downwardly and inwardly extending flanges *h*' for engaging the flanges *g*' of the guide plate, is provided with a transversely extending, rotatable shaft *h*². This shaft carries a hand wheel *h*³ at its outer extremity.

and a pinion h^4 between its bearing points. Spaced grooves g^2 formed in the upper surface of the guide plate g , serve as teeth with which the teeth of the pinion h^4 engage to advance or retract the carriage h along the guide plate g .

A needle frame i is secured to the carriage h by means of bolts i' and is formed with a series of perforations i^2 for receiving needles j . These needles are hollow and carry threads j' , as clearly shown in Figure 1. The needles are provided with enlarged ends j^2 which abut against the needle frame and are held by screws j^3 . By providing a screw 15 with a sufficiently large head, each screw may serve to secure four needles to the frame, the flange of the screw-head engaging the enlarged ends j^2 of the needles at points spaced 90° apart on the periphery of the screw-head.

When the carriage is advanced upon the fabric f carried by the fabric frame, the needles penetrate the fabric and carry the thread through a distance which depends upon the extent of movement of the slideable carriage. After the needle has penetrated the fabric, it moves into the bristles of the brush and upon reverse movement, the thread or yarn is gripped by the bristles to prevent the withdrawal of the yarn with the needles. When the needle is withdrawn from the fabric, the fabric frame e is moved slightly in either a vertical or horizontal plane and the needle frame again advanced into the fabric. By predetermined manipulations of the respective frames, and a suitable choice of colors for the yarns carried by the several needles, various designs and figures may be formed in the pile of the resulting article.

When the fabric base is removed from the frame, the gripping of the loops of yarn by the bristles requires a pull to effect their removal. By pulling on the fabric, the portion of the yarn on the side of the fabric adjacent the needles is drawn tightly against the fabric, resulting in a reverse side, such as shown in Figure 4. After the fabric has been removed and the loops thus pulled, the latter are cut as, for instance, along the dot and dash line shown in Figure 4.

It will be seen that the invention includes broadly any means for advancing and retracting a bank of needles into a suitably positioned fabric base, there being a means for gripping the loops formed when the needles are retracted and a means for moving either or both the fabric and the needles. Although the invention has been described in connection with the specific construction shown in the accompanying drawings, it is not to be limited save as defined in the appended claims.

I claim as my invention:

1. A machine of the character described comprising a fabric frame, a needle frame, 65 a plurality of yarn carrying needles carried

thereby, means to move one of the frames to cause the needles to penetrate the fabric, means on the fabric frame to hold the yarn frictionally after a needle has penetrated the fabric and means to move one frame relatively to the other in a plane parallel thereto. 70

2. A machine of the character described comprising a fabric frame, a needle frame, a plurality of yarn carrying needles carried thereby, means to move one of the frames to cause the needles to penetrate the fabric, a brush on the fabric frame to hold the yarn after a needle has penetrated the fabric and means to move one frame relatively to the other in a plane parallel thereto. 75

3. A machine of the character described comprising a fabric frame, a needle frame, a plurality of yarn carrying needles carried thereby, means to move one of the frames to cause the needles to penetrate the fabric, a brush on the fabric frame to hold the yarn after a needle has penetrated the fabric, means to maintain the bristles of the brush compressed, and means to move one frame relatively to the other in a plane parallel 80 thereto. 85

This specification signed this 7th day of May A. D. 1928.
